UNITED STATES PATENT OFFICE.

CHARLES F. GAUNT, OF BIRMINGHAM, ENGLAND.

MEDAL-RIBBON MOUNT.

Application filed March 10, 1921. Serial No. 451,363.

To all whom it may concern:

Be it known that I, CHARLES FREDERICK GAUNT, of the city of Birmingham, England, a subject of the King of Great Britain, have invented certain new and useful Improvements in Medal-Ribbon Mounts (for which I have filed an application in England April 21, 1917, Patent No. 115,069); and I do hereby declare that the following 10 is a full, clear, and exact description thereof.

This invention has reference to medal ribbon bars or mounts and consists of the herein described improved method of, or means for, permanently attaching a medal ribbon 15 or medal ribbons thereto.

It has previously been proposed for a medal ribbon bar to be formed of trough section with upstanding edges and for the ribbon when folded round the front of the 20 bar and with its ends in the trough to be secured by a wire clip or by a second removable bar secured in the trough by screws or other suitable means, such as by flat headed studs which pass through slots in the removable bar in the trough and it has also 25 been proposed for these studs to be engaged by a split pin at the back. The act of placing the removable bar over the ends of the ribbon or ribbons in the trough has the effect of drawing the ribbon tightly round the 30 front of the ribbon bar and securing the ribbon thereto as when the ribbon bar is fixed the ends of the ribbons are firmly clamped in the trough between the ribbon bar and the removable bar. It has also been proposed 35 for the sides of the trough section ribbon bar to slope inwardly and for the removable bar or keep to be made of corresponding shape with springy sides bent inwardly towards each other and designed to fit within 40 the body and sloping springy sides of the ribbon bar and to secure the ends of the ribbon therein by clamping them between the sloping sides of the ribbon bar and removable bar or keep. Moreover it has been proposed 45 for the removable bar or keep to be furnished with upwardly projecting prongs like the prongs of a paper fastener adapted to pass through the garment and to be opened out at the back of the same so as to secure the ribbon bar thereto.

For the purpose of my invention a medal

ribbon bar consists essentially of two bars namely a front bar and a back bar. The front bar is of elongated form with upstanding parallel side edges so that the bar is of shallow trough section. The back bar is a parallel sided flat section bar the width of which is slightly less than the inside width of the trough of the front bar and the thickness of this back bar is slightly less than the depth of the upstanding sides of the front bar. In fixing the ribbon or ribbons to the ribbon bar, the ribbon is or the ribbons are folded round the front of the front 60 bar and the ends of the ribbon are folded over the sides of the trough and into the interior of the top of the ends of the ribbon or ribbons and there fixed by press tools or the like which close the side edges of the trough firmly on to and around the edges of the back bar and also fixing the ribbon or ribbons to the compound bar. The back bar is preferably fitted with a brooch pin and catch or other suitable means for attachment 65 of the medal ribbon bar to a coat or other garment.

For full comprehension however of my invention reference must be had to the accompanying drawings in which similar 70 reference characters indicate the same parts, and wherein—

Figure 1 is a cross sectional isometrically projected back view of a medal ribbon bar constructed in accordance with this invention shewing also some medal ribbons 75 fixed thereto;

Figure 2 is a cross sectional elevation of the back and front bars of the same separated the front bar being shewn in the 80 shape which it has before its side edges are closed down on to the ribbon and back bar;

Figure 3 is a cross sectional elevation of the same before the side edges of the front bar are closed down on to the ribbon and 85 back bar;

Figure 4 is a cross sectional elevation of a modified form of front bar for the ribbon bar, and

Figure 5 is a cross sectional isometrically 100 projected back view of a modified form of the back bar.

Referring to the drawings it will be seen that the medal ribbon bar consists essentially

Patented Apr. 3, 1923.

UNITED STATES PATENT OFFICE.

ALEXANDER GILLESPIE, OF PITTSFIELD, ILLINOIS.

DEVICE AND PROCESS FOR FEEDING ROLLER MILLS.

Application filed July 18, 1921. Serial No. 485,605.

To all whom it may concern:

Be it known that I, ALEXANDER GILLESPIE, a subject of the King of England, residing at Pittsfield, in the county of Pike and State 5 of Illinois, have invented new and useful Improvements in Devices and Processes for Feeding Roller Mills, of which the following is a specification.

This invention relates to the art of milling 10 flour, and has special reference to improvements in means for feeding wheat to the rolls of a roller mill.

As is well known to those skilled in the art, the two rolls of a roller mill rotate at 15 different rates of speed, the differential speed, or, the rate of rotation of the "slow" roll relative to the "fast" roll, determining the capacity of the machine. In ordinary practice there is located above the two rolls 20 a third, or feed roll, which regulates the amount of grain allowed to pass to the rolls for grinding or reduction.

So far as I am aware, no attempts, prior 25 to my invention, have been made to accurately regulate the amount of grain passed to the grinding rolls, when proper spacing of the grain and the relative speed of feed roll to slow roll are considered, so that when 30 each grain to be ground takes its position on the slow roll and is opened out by the fast roll, it will approximately cover the amount of surface on the slow roll allotted to it, so that the grinding surfaces in action will be fully used to their capacity relative 35 to the highest efficiency. The smooth feed roll is the most used and best known agent of feeding wheat to rolls, but no spacing of the grain fed by it relative to the slow roll can be accomplished with its use, for the 40 reason that, being smooth, the grain is not spaced on it according to any definite plan. Further, I have found that it is the almost universal practice to have the travel of the slow roll never less than 9 to 1 of the feed 45 roll with the result that over-lapping occurs, i. e., grain will be ground upon grain, and, therefore, it is impossible to obtain the full use of the surface of the slow roll in action.

It is, therefore, the object of my invention 50 to provide means whereby the amount of grain passed to the rolls will be regulated according to the surface capacity and speed of rotation of the slow roll, so that exactly the amount of grain that can be ground by 55 the rolls in each revolution of the slow roll will be fed to the rolls.

With this object in view, my invention consists in providing a feed roll having indentations therein regulated in proportion to the surface dimension of the roll, which 60 indentations are continuously filled with individual grains, respectively, and discharge the grain in the revolution of the roll to the grinding rolls, and in proportioning the speed of rotation of the feed roll to that of 65 the slow roll whereby the number of grains of wheat passed to the slow roll in each revolution thereof can be determined with mathematical accuracy.

In the accompanying drawings—

Figure 1 is a view in cross-section of the upper part of a roller mill, showing the general arrangement of grinding and feed rolls in a single type machine;

Figure 2 is a perspective view of the 75 same, a portion of the casing being broken away to better illustrate the construction and the driving mechanism being omitted;

Figure 3 is an ideal sectional view taken on the line 3—3 of Figure 1, viewed in the 80 direction of the arrows, and showing one form of driving connection for the feed and grinding rolls.

Figure 4 is a view in broken elevation on an enlarged scale showing one form of indentation;

Figure 5 is a similar view showing another form of indentation; and

Figure 6 is a similar view showing a still further form of indentation.

Referring now to the drawings, the numeral 1 indicates a casing of a roller mill, mounted in which, in co-operative relation, is a fast roll 2 and a slow roll 3. The shaft 4 of the fast roll is provided with a pulley 5 by means of which it is driven by a belt 6 in the usual way. On one end of the shaft 4 is a conical pulley 7. The numeral 8 indicates a feed roll mounted in the casing above the grinding rolls 2 and 3, the shaft 9 of said feed roll being provided with a conical pulley 10, oppositely disposed with respect to the pulley 7. A belt 11 is passed over the respective pulleys 7 and 10 whereby the feed roll 8 is driven from the shaft 105 of the fast roll 2. The shaft 12 of the slow roll is provided with a pulley 13 by means of which it is driven by a belt 14 in the usual manner. As will be understood, by moving the belt 11 in one direction or the other on the pulleys 7 and 10, the speed of 110 rotation of the feed roll 8 may be varied to

definite and predetermined relation to the surface area of said slow roll.

2. In a roller mill in combination with the differential grinding rolls, a feed roll for feeding grain thereto, and means for regulating the numerical feed of the grain to the grinding rolls by the feed roll to cause the number of grains fed to the grinding rolls in each revolution of the slow roll thereof, to be the same as the total number of a given unit of measurement contained in the surface area of said slow roll, said unit of measurement being a square whose area is substantially equal to the area of a flattened 15 grain of wheat.

3. In a roller mill in combination with the differential grinding rolls, a feed roll having its surface provided with cavities, and means for continuously filling said 20 cavities with individual grains and for delivering the grains from the cavities to the grinding rolls, the number of cavities in the feed roll and the speed of rotation of the feed roll relative to the slow roll, being such that 25 for a single revolution of the slow roll, said feed roll will deliver to the grinding rolls a number of grains whose total area, when flattened out, will substantially equal the 30 surface area of the slow roll.

4. In a roller mill in combination with the differential grinding rolls, a feed roll provided on its surface with cavities, each of which is included within an allotted space of 35 predetermined area and the number whereof bear a definite numerical relation to the surface area of the slow roll, means for supplying grain to the cavities of said feed roll, means for causing said slow roll and feed 40 roll to expose the same amount of surface area for each revolution of the slow roll, and means for rotating said feed roll to cause its cavities to deliver their grain to the differential rolls for grinding.

45 5. In a roller mill in combination with the differential grinding rolls, a hopper located above the same for containing grain, a rotatable feed roll located below the discharge end of the hopper and provided over its 50 periphery with cavities, the totality of the areas allotted to each having a predetermined relation to the surface area of the slow roll, and which cavities are continuously filled with grains from the hopper, 55 and discharge said grains to the grinding rolls in the rotation of the feed roll, means

for rotating all of said rolls, and means for proportioning the surface travel of the feed roll to that of the slow roll to cause the number of grains delivered by the feed roll to be 60 such that the total area of the grains, when flattened out by the fast roll of the differential grinding rolls, will substantially equal the surface area of said slow roll, whereby 65 the latter will be theoretically covered by the grains without overlapping thereof.

6. In a roller mill in combination with the differential grinding rolls, a feed roll having its surface provided with cavities, and means for continuously filling said cavities with individual grains and for delivering the grains from the cavities to the grinding rolls, the number of cavities in the feed roll and the speed of rotation of the feed roll relative to the slow roll, being such that 70 for a single revolution of the slow roll, said feed roll will deliver to the grinding rolls a number of grains whose total area, when flattened out, will substantially equal the 75 surface area of the slow roll, and a variable feed drive for the feed roll operated from one of said grinding rolls, whereby the number of grains delivered by said feed roll to the differential grinding rolls per hour may 80 be varied, if desired, at the will of the operator.

7. The method of feeding grain to the differential grinding rolls of a roller mill, which consists in regulating the numerical feed of the grain to cause the number of 90 grains passed to the grinding rolls per revolution of the slow roll of the differential grinding rolls, to be such that the totality of the area of the flattened grains shall substantially equal the surface area of said 95 slow roll.

8. The method of feeding grain to the differential grinding rolls of a roller mill, which consists in controlling the numerical feed of the grain to cause the number of 100 grains fed to the grinding rolls in each revolution of the slow roll thereof, to be the same as the total number of a given unit of measurement contained in the surface area of the slow roll, said unit of measurement 105 being a rectangular space of given area allotted to each grain fed to the grinding rolls.

In testimony whereof, I have hereunto set my hand.

ALEXANDER GILLESPIE.
